UNITED STATES PATENT OFFICE.

HENRY D. SCHALL, OF DETROIT, MICHIGAN, ASSIGNOR TO DETROIT STOVE WORKS,
OF DETROIT, MICHIGAN, A CORPORATION OF MICHIGAN.

RANGE.

1,338,870.

Specification of Letters Patent. Patented May 4, 1920.

Application filed May 2, 1919. Serial No. 294,160.

To all whom it may concern:

Be it known that I, HENRY D. SCHALL, a citizen of the United States of America, residing at Detroit, in the county of Wayne and State of Michigan, have invented certain new and useful Improvements in Ranges, of which the following is a specification, reference being had therein to the accompanying drawings.

10 This invention relates to ranges and refers more particularly to ranges of the hotel or other large sizes, although the invention in its broader aspects is not limited to the type of heating apparatus mentioned. The present application includes certain subject matter divided out of co-pending application Serial No. 204,533.

The invention resides in the novel construction of the oven section and its arrangement with relation to an adjacent top section; in the construction of the joints between the various insulator sections of the oven so that dissipation of heat is prevented; in the provision of a baffle member between the oven and top plate of the range which baffle also serves as a support for the top plate; in the arrangement of this baffle and the graduated passage between the top wall of the oven and the top plate so as to produce an even distribution of the heat and conserve the heat units; in the novel construction of the oven floor or pan; in the means for guarding against interference with the rise of the heated air within the oven by inserting unduly large pans therein; and in such further features of construction and arrangements and combinations of parts as will more fully hereinafter appear.

40 In the drawings:

Figure 1 is a vertical sectional view through a range embodying my invention;

Fig. 2 is a top plan view of the construction shown in Fig. 1;

45 Fig. 3 is a vertical sectional view on the line 3-3 of Fig. 1;

Fig. 4 is a perspective view of the oven plate;

Fig. 5 is a sectional detail view of an angle bar which is mounted within the oven upon a side wall thereof to limit the size.

of cooking vessels that may be inserted in the oven and insure an upward circulation past such vessels.

Describing in detail the construction shown in the drawings, A designates a range having an open-top plate B and an oven C, the latter being positioned beneath one part of the top plate. For supplying heat to the top plate I preferably employ a plurality of 55 burners D which extend upwardly from supply pipes D', the supply of gas to which is controlled by suitable shut-off valves D². These valves are preferably located in a line 60 at the front of the stove and control the supply from the main pipe or feed line D³.

As shown in Fig. 1 the top plate B is formed in three sections B', B² and B³ which are supported at their edges in grooves or seats E formed in the top flange E' of 70 the body A', which latter may be formed of sheet-metal, or other suitable construction.

For retaining the heat in close proximity to the top plate and preventing its dissipation below the plane of the burners, I employ 75 a burner block F of suitable refractory material, which block is provided with vertical openings F' through which the burners D extend. It will be noticed that the openings are of a sufficiently greater diameter than 80 the burners to permit of surrounding air passages through which the burner units respectively receive a secondary air supply in the chamber G in a manner similar to the well-known Bunsen burner. The secondary 85 air passing through the openings F' is pre-heated by the refractory material, as is likewise the gaseous mixture flowing through the burner tubes, a complete combustion of the gas and a maximum temperature thus 90 being assured.

It will be noted that the section B' of the top plate is located directly above the burners D, the space in between being just sufficient to have the top plate clear the top of 95 the blue flame cone of the burners. This will produce an intense heat on the burner section B' while the hot gases of combustion will then pass from the chamber below the section B' to the chamber below the section B² and from there to the chamber below the section B³. The chambers below the sections 100

B^2 and B^3 taper toward the back so that the gas passage is more restricted as it nears the flue or outlet G' . This tapering passage is produced by varying the thickness of the 5 insulating blocks H and H' forming the top of the oven, and to facilitate the even distribution of heat, there is positioned above the oven a diagonally-extending baffle member or deflector I to compel the gases to 10 travel throughout substantially the entire area of the sections B^2 and B^3 , said member also constituting a supplementary support for the section B^2 . Preferably said member is formed as a rib integrally depending from 15 the middle section B^2 of the top plate.

As shown in Fig. 2, the rib I is arranged to permit a small portion of the gases to pass rearwardly of said rib for heating the rear portion of the top plate while the 20 heater portion of the gases are deflected by said rib toward the forward portion of the stove so as to more intensively heat the front portion of the top plate. The insulating block F is also provided with supporting 25 ribs or projections F^2 which serve to support the section B' of the top plate. Thus the entire top plate is supported not only by the ledge E but also by the ribs or flanges F^2 and I , which being indestructible by heat 30 form a permanent support for said plate.

While the heat to the various sections of the top plate can be varied to suit the temperatures desired, it has been found possible with a range of this kind to maintain the 35 front section B' at about 1200° F., the center section B^2 at 750° F. and the rear section B^3 at about 450° F. When these high temperatures are reached the stack temperature is only about 260° ; these temperatures, of course, being simply illustrative. Also the novel arrangement of the passageways and the baffles beneath the sections B and B^2 allows all the heat units to be advantageously employed.

Referring now in detail to the oven construction, it will be noticed that the side walls and bottom sections J , J' and J^2 are formed of heat-insulating blocks which are preferably made in sections having interlocking joints K . This not only facilitates the assembling of the range but the particular construction of the joint prevents the waste of heat from the oven in the following manner: Each of the joints is formed, 45 with an upper horizontal portion K' , a lower horizontal portion K^2 and a vertical connecting portion K^3 . In each case the blocks are so arranged that the lower horizontal portion is at the outside of the wall. Therefore, in attempting to escape through the 50 joints the heated air will be compelled to pass downward through the vertical portion K^3 in order to escape. As the tendency of the heated gas is to rise, this particular 55 construction of joint will, to a material ex-

tent, prevent the escape of the heated air from the oven. The same stepped joint construction is also employed in the insulator blocks L surrounding the burner section. Another feature of the oven construction 70 resides in the formation of a supporting pan M which is located above the oven burners N . As shown in Fig. 7, the oven plate M is formed with inverted U -shaped ribs O which are spaced apart and the intermediate por- 75 tions O' perforated at O^2 .

This construction of the plate M gives the same a desirable strength and not only eliminates the danger of burning the article in the oven but also provides greater radiating surface, and the perforations permit of the free circulation of the air. A further feature that increases the efficiency of the range is the enameling of the refractory blocks F , H and H' so as to deflect the heat 80 to the top and prevent downward dissipation of heat either to the chamber G or to the oven.

At R is designated a cooking vessel, as a roaster, which may rest upon the plate M , 90 the heated air and products of combustion rising between said vessel and the sides of the oven. To insure the provision of equal spaces for upward circulation at each side of the vessel and to also prevent the use of 95 an unduly wide vessel such as might seriously interfere with such circulation, a pair of angle strips S is horizontally secured to each side wall of the oven, said strips having openings T through which the hot air 100 and gases may rise, inclined tongues U being struck upwardly from said openings and preventing closing of the same in case said angle strips are improperly used, as indicated in dash lines in Fig. 5, as supports 105 for a pan or other cooking vessel.

What I claim as my invention is:

1. In a range, the combination with an oven, of burners positioned in the lower part of the oven, a door opening located at 110 the front of the oven, and a supporting plate positioned above said burners and having a plurality of integrally formed U -shaped ribs, said plate being perforated to assist the circulation of the heat and having 115 the upper surface of said ribs located substantially in the plane of the lower edge of the oven door opening, said ribs running lengthwise of the oven toward the front.

2. In a range, the combination with an 120 oven, of a member secured to a wall of the oven interiorly thereof for spacing cooking vessels from said wall and insuring a free rise of the hot gases past such vessels, said member having openings therein for passage of the gases, and tongues being struck 125 upwardly from said openings.

3. In a range, the combination with an oven, of a pair of angle bars secured to the side walls of said oven and extending sub- 130

stantially from front to back of the oven, said bars forming spacers to maintain circulation spaces at each side of a vessel within the oven and being formed with circulation openings.

4. In a range, the combination with an oven, of burners positioned in the lower

part of said oven, a supporting plate positioned above said burners having a plurality of integral U-shaped ribs and perforated to assist the circulation of the heat.

In testimony whereof I affix my signature.

HENRY D. SCHALL.
